UNITED STATES PATENT OFFICE.

SAMUEL T. SMITH, OF LOS ANGELES, CALIFORNIA.

EVAPORATOR.

Application filed May 26, 1923. Serial No. 641,586.

To all whom it may concern:

Be it known that I, SAMUEL T. SMITH, a citizen of the United States, residing at Los Angeles, in the county of Los Angeles, 5 State of California, have invented a new and useful Evaporator, of which the following is a specification.

My invention relates particularly to what is known as the absorption process for recovering gasoline from natural gas.

It is common practice to recover gasoline from natural gas, this recovery being accomplished either by a process of refrigeration or by absorption. In the absorption system a petroleum oil, having the general characteristics of what is known as mineral seal oil is used as a circulating medium or menstruum being circulated through an absorption tower in which it is finely divided and through which the natural gas to be treated is also circulated. The tower is so constructed that oil and gas are brought into intimate contact with each other therein, the gasoline carried in the gas being absorbed in the body of the oil, the absorbed gasoline and oil being then withdrawn from the absorption tower.

My invention relates to the recovery of the gasoline from the absorbing medium. 30 The principal object of the invention is to provide an evaporator by means of which the gasoline can be readily and efficiently separated from the absorbing medium.

Further objects and advantages will be set forth more in detail hereinafter.

In the drawings which are submitted merely for the purpose of illustrating a particular and practical embodiment of my invention,

40 Fig. 1 is an elevation partly in section of an embodiment of my invention.

Fig. 2 is a section on a plane represented by the line 2-2 of Fig. 1.

45 Fig. 3 is an enlarged view of a portion of the apparatus.

Fig. 4 is a similar view at right angles to Fig. 3.

50 While my apparatus can be fabricated in many forms, I prefer to build it up of cast sections 11, each of which consists of a circumferential wall 12 having flanges 13 and a continuous septum 14. The septum 14 is provided with upwardly extending bosses 15, a vertically disposed hole 16 extending downwardly through the center of each boss. Short bosses 17 are provided

on the bottom of the septum about the hole 16 for the purpose of providing lips. Over the top of each of the bosses 15 I provide a deflector 20, each of which consists of an inverted cup having notches 21 in the edge thereof. A cover 30 is secured to the top section 12 and a tight bottom 31 is secured to the bottom section 11. A vapor outlet pipe 32 is connected into the top 30 and is attached to a vacuum pump 33. The mixture of absorbing medium and gasoline is delivered into the top of the apparatus through a pipe 34 having a valve 35, and the spent absorbing medium is withdrawn from the bottom of the apparatus through a pipe 36 having a valve 37. Directly below each of the septums 14 is placed a steam pipe 40, this pipe being supplied with steam through pipe 41 and the exhaust steam being withdrawn through pipe 42. The pipes 40 are supported directly below septum 14 and above the top of the deflectors 20, the steam coil being so shaped and placed that the turns thereof come directly below the holes 16. Suspended below each of the holes 16 is a distributor pan 50 consisting of a sheet metal pan secured to the lower side of the septum 14 by any convenient means such as the lugs 51 and screws 52. The pans have a bottom 53 which slopes in towards the center of the hole 16 and the pipe 40, and a plurality of fine holes 54 are provided in the bottom of the pans for the purpose of uniformly distributing the absorbing medium over the top of the pipes 40.

85 The method of operation of my invention is as follows:

The absorbing oil containing the absorbed gasoline is delivered through the pipe 34 and is spread over the upper surface of the upper septum 14, rising to the top of the bosses 15. The liquid then runs down in a fine stream through the hole 16 and is distributed by the pans 50 upon the top of the steam coil 40, flowing downwardly thereover in a thin film. The liquid then collects on the next septum 14, building up a shallow pool of liquid thereon and flowing downwardly through the holes 16 in the bosses 15 thereon. The liquid thus flows downwardly through the apparatus, building up a pool on the top of each of the septums and flowing downwardly through the hole 16 and over the steam pipes 40. The liquid is therefore gradually heated in its downward passage at the same time the vacuum pump 33 partially exhausts any

vapor that is formed, this reduction in pressure greatly assisting in the evaporation in the gasoline from the absorbing medium. The heated gasoline vapors passing upwardly through the holes 16 thus exert some slight pressure on the liquid beneath each of the deflectors 20, forcing this liquid downwardly and allowing the gasoline vapor to pass through the notches 21 and bubble upward through the pool of liquid on the septum 14. The gasoline vapors thus pass constantly upwardly, bubbling in turn through each of the pools of liquid and finally being withdrawn by the vacuum pump 33 through the pipe 32. The absorbing medium which finally reaches the bottom of the apparatus is substantially free from gasoline vapors and is withdrawn through the pipe 36 and cooled before being put back in the absorbing tower.

While I have described my invention as applied to the removal of gasoline vapors from an absorbing medium, it should be understood that I do not limit myself to this particular application, the scope of my invention being only determined by the claims.

I claim as my invention:

1. An evaporator comprising: walls forming a gas tight enclosure; septums extending across said enclosure so placed as to form pools of menstruum on the upper surface thereof; a series of bosses on said septums extending upwardly therefrom and each having a vertically disposed hole therethrough; a series of deflectors each being placed over one of said bosses and forming an inverted cup extending downwardly about said boss; a series of heating coils, each coil being placed below one of said septums and above the menstruum carried on the next lower septum, each turn of the heating coil being so placed that the drip through said vertically disposed holes falls on said heating coil; means for delivering liquid to the space above an upper septum; means for withdrawing liquid from the space below a lower septum; and means for withdrawing vapors from the top of said enclosure.

2. An evaporator comprising: walls forming a gas tight enclosure; septums extending across said enclosure so placed as to form

pools of menstruum on the upper surface thereof; a series of bosses on said septum extending upwardly therefrom and each having a vertically disposed hole therethrough; a series of deflectors each being placed over one of said bosses and forming an inverted cup extending downwardly about said boss; a series of heating means, each placed below one of said septums and above the menstruum carried on the next lower septum, said heating means being so placed as to receive liquid from said holes; a distributor secured to the lower surface of each septum below each of said holes, each distributor being so placed as to spread the oil over said heating means; means for delivering liquid to the space above an upper septum; means for withdrawing liquid from the space below a lower septum; and means for withdrawing vapors from the top of said enclosure.

3. An evaporator comprising: walls forming a gas tight enclosure; septums extending across said enclosure so placed as to form pools of menstruum on the upper surface thereof; a series of bosses on said septums extending upwardly therefrom and each having a vertically disposed hole therethrough; a series of deflectors each being placed over one of said bosses and forming an inverted cup extending downwardly about said boss; a series of heating coils, each coil being placed below one of said septums and above the menstruum carried on the next lower septum, each turn of the heating coil being so placed that the drip through said vertically disposed holes falls on said heating coil; a distributor secured to the lower surface of each septum below each of said holes, each distributor being so placed as to spread the oil over said heating means; means for passing a heating medium through said heating coil; means for delivering liquid to the space above an upper septum; means for withdrawing liquid from the space below a lower septum; and means for withdrawing vapors from the top of said enclosure.

In testimony whereof, I have hereunto set my hand at Los Angeles, California, this 16th day of May, 1923.

SAMUEL T. SMITH.
